UNITED STATES PATENT OFFICE.

RICHARD WEBSTER HUDSON AND JOSEPH EDWIN HUDSON, OF TOLEDO, OHIO.

TWIST-DRILL MACHINE.

1,342,963.

Specification of Letters Patent.

Patented June 8, 1920.

Application filed July 29, 1918. Serial No. 247,306.

To all whom it may concern:

Be it known that we, RICHARD WEBSTER HUDSON and JOSEPH E. HUDSON, citizens of the United States, residing at Toledo, in the county of Lucas and State of Ohio, have invented certain new and useful Improvements in Twist-Drill Machines; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

In the manufacture of twist-drills in which the spiral grooves or flutes of the instrument are formed by cutters or chasers, the method of forming first one of the flutes, then, co-axial therewith and equidistant therefrom, another flute, and then grinding the drill, truing the same, and removing burs, is found to be slow, tedious and expensive owing to the number of operations required.

Our invention is designed to largely overcome the difficulties and objections here indicated, and to provide a machine by means of which a completed twist-drill may be rapidly, cheaply and accurately produced by substantially a single operation, and in which loss by breaking or injuring the drills or cutters is reduced to a minimum.

To these ends our invention consists of the devices, construction and arrangement of parts hereinafter described, and illustrated in the accompanying drawings, in which—

Figure 1 is a top plan-view of our machine; Fig. 2, a side-elevation of the same with portions in central vertical section to disclose the construction and operation of the "leaders" hereinafter referred to; Fig. 3, a rear-elevation of a portion of our machine which carries the clearing or finishing cutters hereinafter referred to; Fig. 4, a front end-view of the "turret" or device for carrying and presenting to the several cutting instruments employed the blanks to be operated upon in the successive steps of their treatment; Fig. 5, a rear end-view of the same showing the group of gears for actuating the leaders; Fig. 6, a side-elevation of one of the "leaders" hereinafter referred to, detached; Fig. 7, a side-elevation of a sleeve for rotatably and slidably sup-

porting the leader illustrated in Fig. 6; Fig. 8, a side-elevation of the sleeve hereinafter referred to, designed to carry a central driving pinion and worm-wheel, and a pinion for backing the leaders away from the cutters of the machine; Fig. 9, a front-elevation of a portion of our machine, showing the pair of flute-cutters hereinafter referred to, together with the devices for gradually and slightly decreasing the cut and for automatically releasing the flute-cutters and the clearing cutters from the work to permit the removal of a finished drill and the introduction of a blank; Fig. 10, a diagram illustrating the relation of the pair of flute cutters to each other and to the work with which the cutters are engaged, and Fig. 11, a diagram of the clearing and finishing cutters hereinafter referred to, in operative engagement with the fluted drill together with the instruments for removing the bur formed by the cutters.

Like letters and numerals of reference indicate like parts throughout the drawings.

Upon a stout table or bench 1 is journaled a driving shaft 2 carrying fast and loose driving pulleys 3 or equivalent driving device. Upon the inner end of the shaft 2 is secured a double pinion 4 beveled on its inner portion. The teeth at one side of the pinion 4 engage and drive a pinion 5 which in turn engages and drives a gear 6 on shaft 7. The teeth on the other side of the pinion 4 engage the teeth of a gear 8 mounted on shaft 9. The shafts 7—9 are journaled in sleeves or bearings 7^a and 9^a and their axes are disposed in vertical planes which converge,—in the present instance, for illustration,—at an angle of 28 degrees. This angle may, of course, be varied as circumstances may require. The shaft 7 carries at its inner end a milling cutter 10, and the shaft 9 carries at its inner end a like milling cutter 11. The cutters 10 and 11 are arranged, in this instance, one exactly above the other and are separated according to the depth of the flute to be cut upon the intervening drill-blank, the arrangement being such that the two cutters operate simultaneously upon opposite sides of a drill blank in spiral grooves, the cutters being rotated in oblique planes which correspond to the lead of the grooves.

The rotation and forward feed of the blanks to be operated upon is obtained by means of the mechanism now to be described.

Upon shaft 12 is journaled a casing 13, a front view of which is seen in Fig. 4, and a rear view in Fig. 5. This casing being revoluble upon a fixed horizontal shaft may be regarded as a horizontal "turret." Within the casing 12 and parallel with its axis are three equi-distantly arranged leaders 14, such as are indicated in Fig. 6. These at their forward ends project through holes 15 in plate 16 which forms the front of the casing 12, and each is provided at its forward end with a chuck 17 adapted for operative engagement with the end of a twist drill blank. The leaders 14 slide longitudinally in and are revoluble with their respective sleeves 18, each of which is revoluble in a sleeve or tubular portion 19, of which there are 3, the group being formed integral with the plate 16 and forming together the body 20 of the "turret." The sleeve 18 at its outer end is provided with a toothed ring or pinion 20. The leaders 14 are longitudinally slotted as at 21, these slots being engaged by splines 22 projecting inwardly from the sleeve and which engage the slots 21 in the leaders 14. It will be seen that the member 14 must rotate with the sleeve 18 but is permitted to slide longitudinally therein. The leader 14 is provided with a spiral groove 23 having the same lead as the flute to be cut upon the drill-blank. This groove is engaged by the inwardly projecting lug 24 (see Fig. 4) which upon the leader 14 being rotated causes it to advance or recede as the case may be. Each of the three pinions 20 upon the sleeve 18 is in engagement with a central pinion 25 formed on or secured to one end of sleeve 26 which is loose upon the shaft 12. When the sleeve 26 is revolved the several pinions 20 and sleeves 18 are rotated in unison therewith (see Fig. 5). The rotation of the sleeve 26 and its associated parts just referred to is effected through the worm-wheel 27 secured to sleeve 26, driven by a worm 28 on shaft 29 which carries beveled pinion 30. This pinion engages and is driven by a corresponding pinion 31 on one end of shaft 32. The other end of shaft 32 carries a beveled pinion 33 engaged with and driven by a pinion 34 on one end of shaft 35, the other end of which carries a pinion 36 engaged with and driven by pinion 37 on one end of shaft 38, the other end of which carries a pinion 39 engaged with and driven by the gear-wheel 8.

The sleeve 26 carries in addition to pinion 25 and to worm wheel 27, a pinion 40 which engages and is driven by a pinion 41 which, when the worm wheel and worm 27-28 are disengaged, may be operated by the hand-crank 42 to rapidly reverse the gears which rotate and project the leaders 14 and to thus withdraw the work from the cutters and to permit the introduction of a fresh blank.

65 The automatic disengagement of the worm

28 from the worm wheel 27, which permits the manual operation just indicated, is effected by dropping one end of the shaft 29 upon which the worm is fixed, so that the worm and worm-wheel are out of engagement. The shaft 29 at its end opposite the cam 43 has bearings arranged to permit this slight tilt of the shaft. One end of the shaft 29 is vertically slidable and is supported by a cam 43 (see Fig. 1) the other end being loosely journaled as above indicated. The cam 43 is connected with one end of and controlled by a rod 44, the other end of which is connected with a lever 45 fixed and fulcrumed at its lower end upon shaft 46. The upper end of the lever 45 is engaged by the forward end of one of the leaders 14 at or near the chuck 17. When the leader has been fed forwardly the distance necessary to finish the work upon the drill-blank, the lever 45 has been swung upon its bearing, moving the rod 44 and tilting the cam 43 with its flat side uppermost so that the shaft 29 is permitted to drop slightly and so that the worm and worm-wheel are now disengaged. Now by means of the hand-wheel 42 the leaders may be quickly retracted to their original position. A handle 47 fixed upon the shaft 46 serves to swing the lever 45 to project and retract the leaders as well as to throw the several cutters or chasers into and out of engagement with the work.

This control of the chasers or cutters by means of the handle 47 is attained by means of the devices and arrangement now to be described.

The sleeves 7^a and 9^a in which the shafts 7 and 9 are journaled are secured respectively to the top of a block 7^b and 9^b arranged to slide vertically in the machine head which carries the shafts, pulleys, and gears, numbered from two to nine, inclusive, parts 7^b-9^b being indicated in dotted lines in Fig. 1. From the top of this head springs a standard 48 upon which is fulcrumed, as at 49, a horizontal bar 50. At one side of the fulcrum 49 is pivoted, as at 51, a link 52 which is engaged, as at 53, with the block or member 7^a. At the opposite side of the fulcrum 49 is pivotally engaged, as at 54, a link 55 which is engaged, as at 56, with the block 9^a (see Fig. 9). The points 51-54 are equi-distant from the fulcrum 49 so that when the arm 50 is swung on its fulcrum the blocks 7^a-9^b are correspondingly raised or lowered and the cutters 10-11 are correspondingly caused to approach or recede from each other. The movement of the arm 50 is effected by a rod 57, the upper end of which is pivoted, as at 58, to one end of the bar 50, the lower end being operatively connected, as at 59, with a cam 60 fixed on the shaft 46. By means of an adjusting screw 57^a the length of the connection 57 may be controlled and the normal distance 130

between the cutters 10—11 may be established as may be desired. It will now be seen that when the leader which actuates the lever 45 has been projected sufficiently to 5 tilt the shaft 46 to which the lever is secured, the cam 60 will be turned with its flat side uppermost which permits the rod 57 and the end of the arm 50 to which it is attached to drop suddenly, thus lowering the 10 cutter 10 and correspondingly raising the cutter 11. This quick separation is facilitated by a suitably located spring 50^a. This separation of the cutters 10 and 11 simultaneously with the disengagement of the 15 turret from the worm 28 permits the rapid retraction of the leaders through the rotation of the hand-wheel 42 so that a finished drill may be removed and so that a fresh blank may be placed in its appropriate chuck.

20 The contour of the cam 60 is such that just before the cutters are swung asunder as just described, they are gradually moved slightly apart so that the depth of the cut of each of the flute cutters is gradually and slightly 25 decreased, thus thickening and strengthening the web of the drill at its junction with the shank of the drill.

30 The turret 13 while it is disengaged from the worm 28 may be rotated on its shaft 12. A step by step rotation of the turret is permitted by means of a spring latch 61 controlled by a handle 62, the latch being adapted for engaging with three equidistant notches 63 in the edge of the plate 16 forming the front of the turret. The latch 61 and the notches 63 hold the turret and the several chucks 17 in operative relation to the cutters 10 and 11, as well as to a pair of 35 milling, clearing, or finishing cutters to 40 which the partly finished twist drill is moved by the swing of the turret, and which with their controlling mechanisms are now to be described.

45 64 and 65 indicate milling, finishing or clearing cutters, disposed one above the other, mounted in the same plane upon shafts 64^a and 65^a respectively. These shafts are journaled in sleeves 66 carried by frames 67 and 68 (see Fig. 3) mounted and vertically movable in a housing 69. The shaft 64^a carries at its end, opposite the cutter 64, a beveled pinion 70 engaged with a corresponding pinion 71 at one end of shaft 72 the other end of which carries a beveled 50 pinion 73 which is engaged and driven by the beveled gear 37 which is operated in the manner hereinbefore described. The shaft 72 carries a pinion 74 which engages and drives a pinion 75 on one end of shaft 55 60 76, the other end of which carries a beveled pinion 77, indicated in dotted lines in Fig. 1,—the latter pinion engaging and driving a corresponding pinion, not shown in the drawings, fixed on the shaft 65^a.

65 The cutters 64—65 are positioned so that

a point exactly midway between the two coincides with the axis of one of the leaders 14 when turned to such position that the spring latch 61 engages a notch 63 in the turret.

70 Since the leaders 14, the flute cutters 10 and 11 and the clearing or finishing cutters 64—65 are all driven from one pulley, it is important, in order to prevent injury or breakage of the machine or the drills, that they be started and stopped simultaneously. The starting and stopping of the leaders and the flute cutters has already been described. The automatic separation of the 75 cutters 64—65 at the end of their cut to permit the withdrawal of the twist drill is effected by means of a lever 78 fulcrumed as at 79. The lever at one side of its fulcrum is connected by means of a link 80 with the frame 67 which carries the cutter 64 and is correspondingly connected at the opposite side of its fulcrum by means of link 81 to the frame 68 which carries the cutter 65. Now the swing of the lever 78 causes the frames 67—68 to move vertically in opposite directions, thus separating or bringing closer together the cutters. The outer end of the lever 78 carries a rod 82, the lower end of which is operatively connected with a cam 83 fixed on the rod 46. The normal 80 separation of the cutters 64—65 is governed by a screw connection,—as indicated at 78^a,—between the lever 78 and the rod 82. A spring 84 holds the lower part of the rod 82 in close contact with the cam 83 so that 85 when the flat side of this cam is turned uppermost the lever 78 is quickly moved to disengage the cutters 64—65 from the work.

90 The operation of our machine thus far described is as follows:

95 The belt-pulley being in motion, the handle 47 being swung so that the pairs of cutters 10—11, 64—65, are separated and so that the worm 28 is thrown out of gear, the leaders in the turret being also in retracted position, a blank is placed in the uppermost chuck 17, being the one which will next move into alignment with the cutters 10—11. Now by means of the hand wheel the work is brought close to the cutters 10—11. Next, 100 the handle 47 is depressed, thus bringing into operative relation the several cutters and at the same time, through the worm gear 27—28 and the gears 20—25, feeding 105 and revolving the blank between the flute-cutters in the manner hereinbefore indicated. When the cut upon the blank has proceeded the required distance, the lever 45 is automatically thrown over, the shaft 46 is turned, cams 60 and 83 are actuated, and the cutters are thereby forced asunder, 110 at the same time throwing the worm 28 out of gear. Now, the spring latch 61 being released, the work is by means of the hand wheel 42 withdrawn sufficiently to permit 115 120 125 130

the turret to be given a one-third turn which brings the drill which has just been grooved into alignment with the cutters 64—65. A green blank having, in the mean time, been placed in its appropriate chuck, it is by this part turn of the turret brought between the fluting cutters, and the operation just described is repeated. At each stop in the turn of the turret one blank is removed and another is supplied. Between successive stops a blank is spirally grooved, and another blank is milled and finished. Thus at each revolution of the turret a completed drill is produced.

15 The cutters 64 as they cut transversely across the surface of the advancing revolving drills, leave at the edges of the spiral grooves or flutes a slight bur which we remove by the mere withdrawal of the drill 20 from its advanced position between the cutters. To accomplish this we provide a pair of stout scrapers 85 (see Fig. 11), positioned at opposite sides of and in close contact with the drill. As the revolving drill is withdrawn from between the finishing cutters the scrapers 85 remove the bur, thus obviating the necessity for the usual grinding.

The machine-head which carries the driving pulley and its associated gears is mounted on ways, as indicated by the dotted lines at 86 in Fig. 1. By means of a screw 87 having a graduated head 88, the machine-head is moved to and fro to accommodate the varying thicknesses of the cutters 10—11 35 and to cause the cutters to coincide with the size-number of the drill-blanks, as indicated by the numerals on the graduated plate 88. The housing 69 in which the cutters 64—65 are mounted is adjustable on the bench or 40 table of the machine by means of an adjusting screw 89. The frame in which the turret 13 is mounted is also adjustable on the bench or table by means of adjusting screw 90. These adjustments are well understood 45 and need not be here further described.

Having described our invention, what we claim and desire to secure by Letters Patent is—

1. In a machine of the described character, in combination with fluting cutters and finishing cutters, a longitudinally-fixed rotatable turret, a plurality of holders mounted in the turret and adapted respectively for operative connection with a drill-blank, 50 gears mounted and journaled upon the turret and adapted and arranged to simultaneously rotate the holders, means whereby the rotation of the holders will also project and retract the holders into and out of operative 55 relation to the cutters, and a detent arranged to engage and hold the turret and the holders successively in operative relation to the cutters.

2. In a machine of the described character, a cutting mechanism adapted and ar-

ranged to cut spiral grooves upon a blank, a cutting mechanism adapted and arranged to clear or finish the grooved blank, a longitudinally-stationary rotatable turret, a plurality of holders mounted in the turret, each 70 holder having a chuck adapted for operative connection with a drill-blank, said turret being adapted and arranged to successively present a blank to the cutting mechanism first mentioned and then to the second mentioned cutting mechanism, a detent adapted to engage and hold the turret in operative relation to either of said cutting mechanisms, means carried by the turret for simultaneously projecting said holders into operative relation to said cutting mechanisms, and gears journaled upon the turret adapted to rotate the holders during such projection, to conform to the lead of the spiral grooves 75 to be formed by the fluting cutters. 80

3. In a twist drill machine, a pair of cutters arranged to simultaneously cut spiral grooves in a drill-blank, a blank-carrier, a turret in which said carrier is rotatably and reciprocably mounted, gears carried by and 90 journaled upon the turret adapted to rotate and reciprocate the blank-carriers in conformity to the lead of the grooves to be cut, a worm-drive for actuating said gears in one direction, and a quick acting manually operated drive for actuating said gears in the 95 opposite direction.

4. In a twist drill machine, a pair of cutters arranged to simultaneously cut spiral grooves in a drill-blank, a cutting mechanism adapted to clear such blanks, a series of blank-carriers, a turret in which said blank-carriers are rotatably and reciprocably mounted and in which they are in succession presented to said cutting mechanisms, gears carried by the turret and which feed and rotate the blank-carriers in conformity to the lead of the grooves to be cut, quick-acting gears for retracting said blank-carriers, and devices which co-act to disengage said cutting mechanisms from the work and to throw out of gear said feeding gears. 105

5. In a twist drill machine, a pair of cutters arranged to simultaneously cut spiral 115 grooves in a drill-blank, and a cutting mechanism adapted to clear the grooved blank, combined with a turret, blank-carriers rotatable and reciprocable in the turret, said turret being arranged to successively present said carriers first to said pair of cutters and then to said cutting mechanism, gears carried by the turret adapted to rotate and reciprocate the blank-carriers in conformity to the lead of the grooves to 120 be cut, a worm-drive which actuates said gears in one direction, and a quick acting manually operated drive which actuates said gears in the opposite direction. 125

6. In a drill making machine, a pair of 130

- cutters arranged to simultaneously cut on opposite sides of a drill-blank two spiral grooves, said cutters being disposed obliquely to each other in planes corresponding to the lead of such grooves, a blank holding chuck in operative relation to said cutters, a leader having a spiral groove and a longitudinal groove and which carries the chuck, a non-reciprocable sleeve co-axial 5 with the leader and with which the leader is slidably and rotatably connected, and gears for rotating said sleeve.
7. In a machine of the described character, a cutting mechanism adapted and arranged to cut spiral grooves upon a blank, a cutting mechanism adapted and arranged to clear or finish the grooved blank, a longitudinally-stationary rotatable turret, a plurality of holders mounted in the turret each 10 holder having a chuck adapted for operative connection with a drill-blank, said turret being adapted and arranged to successively present a blank to the cutting mechanism first mentioned and then to the second mentioned cutting mechanism, a detent adapted 15 to engage and hold the turret in operative relation to either of said cutting mechanisms, means carried by the turret for simultaneously projecting said holders into operative relation to said cutting mechanisms, gears journaled upon the turret for rotating the holders during such projection, to conform to the lead of the spiral grooves 20 to be formed by the fluting cutters, for said gears a worm-drive; also a quick acting manually actuated drive adapted to simultaneously project or retract said holders, and devices for automatically and simultaneously throwing said worm-drive out of 25 gear and disengaging the groove-cutting mechanism from the work at a predetermined point in the advance of the holders.
8. In a machine of the described character, a cutting mechanism adapted and arranged to cut spiral flutes upon a drill-blank, a cutting mechanism adapted and arranged to finish such fluted drill-blank, 30 devices for projecting and retracting such blanks into and out of operative engagement with such cutters, and a scraper 50 arranged to contact with a blank during its withdrawal from the finishing cutter.
9. In a device of the described character, a cutting mechanism, devices for projecting and retracting a blank into and out of operative engagement with such cutting mechanism, means for rotating the blank during its advance and retreat, and a scraper adapted to contact with such blank during its retraction, to effect the removal of such bur 55 as may be formed by such cutting mechanism.
10. A machine of the described character comprising in its construction a pair of milling cutters adapted and arranged to simultaneously cut spiral grooves or flutes on opposite sides of a blank, a pair of milling cutters adapted and arranged to cut upon opposite sides of the blank so grooved, a turret, three holders in said turret adapted respectively to hold a twist-drill blank, a detent adapted to hold the turret and its holders in operative relation to said cutters, means carried by the turret for projecting blanks carried by said holders into operative engagement with said cutters, means carried by the turret for rotating said holders during their advance and retreat, means for simultaneously and automatically releasing all of said cutters from the work and for 65 throwing out of operative relation said projecting means at a predetermined point in the advance of such blanks, means for manually rotating and retracting the holders from the cutters, and a scraper adapted 70 for engagement with the finished blank during its retreat from the finishing cutter.

Correction in Letters Patent No. 1,342,963.

It is hereby certified that in Letters Patent No. 1,342,963, granted June 8, 1920, upon the application of Richard Webster Hudson and Joseph Edwin Hudson, of Toledo, Ohio, for an improvement in "Twist-Drill Machines," an error appears in the printed specification requiring correction as follows: Page 5, after line 87, insert the following as claim 11:

11. *In a twist drill machine, a pair of spindles disposed one above the other in planes converging at one side of the blank to be cut, a fluting cutter carried by each of said spindles, a driving shaft, gears intermediate said driving shaft and said spindles whereby the spindles are rotated, bearings in which the spindles respectively rotate, a bar fulcrumed between and operatively connected with said bearings, means for feeding a drill-blank to said cutters, and devices for tilting the bar on its fulcrum in harmony with the movement of the drill-blank.;*

and that the said Letters Patent should be read with this correction therein that the same may conform to the record of the case in the Patent Office.

Signed and sealed this 6th day of July, A. D., 1920.

[SEAL.]

M. H. COULSTON,
Acting Commissioner of Patents.
